Des. 201,738
Patented July 20, 1965

201,738

ASH TRAY

Richard S. Karbo, Whittier, Calif., assignor to Sutone Corporation, Paramount, Calif., a corporation of California

Filed May 13, 1963, Ser. No. 74,862

Term of patent 3½ years

(Cl. D85—2)

Fig. 1.

Fig. 2.

Fig. 3.

Fig. 4.

Fig. 5.

Fig. 6.

Fig. 7.

Fig. 8.

FIG. 1 is a front elevational view of an ash tray showing my new design;

FIG. 2 is a top plan view of the same;

FIG. 3 is a bottom view;

FIG. 4 is a side elevational view of one side of the ash tray shown in FIG. 1;

FIG. 5 is a side elevational view of the other side thereof;

FIG. 6 is a back elevational view;

FIG. 7 is a perspective view; and

FIG. 8 is a similar view with the cover in opened position.

The dominant features of my design reside in the portion shown in full lines.

I claim:

The ornamental design for an ash tray, substantially as shown and described.
